Primary Examiner — Mary Ann Calabrese**CLAIM**

The ornamental design for a barcoded bloodband with adjacent labels, substantially as shown and described.

DESCRIPTION

FIG. 1 is a top, front, and left side perspective view of a bloodband with adjacent labels, as shown and described shown with one of the labels partially removed.

FIG. 2 is a top plan view thereof;

FIG. 3 is a bottom plan view thereof;

FIG. 4 is a rear elevational view thereof;

FIG. 5 is a front elevational view thereof;

FIG. 6 is an enlarged side elevational view thereof; and,

FIG. 7 is an opposite side elevational view thereof.
